UNITED STATES PATENT OFFICE

2,068,569

CIRCUIT BREAKER

John Rog, Brooklyn, N. Y.

Application April 8, 1935, Serial No. 15,279

1 Claim. (Cl. 200—113)

This invention relates to that class of electrical devices which interrupt the flow of current when too great a load is interposed in the circuit, known as fuses, which at a certain value of current and time rupture the circuit.

Fuses as commonly made require replacement after becoming "blown" or having served their purpose of causing cessation of current, and such replacement is usually inconvenient to accomplish under any condition and particularly so in the dark; moreover, a substitute fuse is not always at hand.

It is therefore an object of the present invention to provide a circuit breaker to be inserted in the circuit, that is instantly responsive to an excess of heat, caused by the current passing therethrough, and break the circuit, cutting off the current.

A further feature is in the provision of means within the circuit breaker for reinstating the flow of current automatically after a momentary overload, entirely without manual effort, this being self-resetting.

Another purpose is to produce an automatic resetting circuit breaker of neat appearance, inexpensive construction and capable of long extended service.

These advantageous objects are attained by the novel construction, combination and arrangement of few and simple parts hereinafter described and illustrated in the accompanying drawing; forming a material part of this disclosure, and in which:—

Figure 1 is a side elevational view of an embodiment of the invention as assembled ready for use.

Figure 2 is a partial side elevational, partial longitudinal sectional view of the same drawn to an enlarged scale.

Figure 3 is a longitudinal sectional view taken on line 3—3 of Figure 2.

Figure 4 is a transverse sectional view taken on line 4—4 of Figure 3, showing the circuit closed.

Figure 5 is a similar sectional view taken in the same plane, but showing the circuit breaker in an open position.

As shown in the drawing the device consists of a tubular casing 10 of insulating material, as insuated fiber, into the socket connecting end of which is set a sleeve 11, having at its outer extremity a disc 12 of dielectric material provided at its outer face with a hub-like extension 13.

The extending portion of the sleeve 11 has 55 formed on it the usual standard screw thread

and is enveloped in a screw shell 14 of conducting material, provided with an inreaching annular flange 15 by which the disc 12 is tightly clamped against the end of the sleeve 11.

The upper edge of the shell makes contact with 5 the adjacent edge of the casing 10 and constitutes a plug adapted to engage a standard socket.

Fixed in an internal longitudinal groove 17 of the casing 10 is a conductor strip 18 having its lower end 19 in electrical engagement with the 10 shell 14 and at its opposite, outer end is a contact block 20, such as carbon, held rigidly to it by a bolt 21, this block extending radially into the hollow casing 10 near its outer end.

Fixed on the outer side of the disc hub 13 is a 15 button shaped conductive contact 22 having a stem 23 passing axially through the disc 12, and formed on the stem is a thin, coiled bi-metallic helix constituting a thermostatic coil 24, extending centrally into the casing 10 towards its outer 20 end.

The upper end of the helix is inbent as at 25, and fixed to a collar 26 firmly secured on an axial conductor rod 27 freely rotatable in the casing and extending from a point near the disc 25 12 to the outer end of the casing where it passes through a central opening in a disc 28 of dielectric material, such for instance, as mica.

The disc 28 acts as a cover for the casing 10 and is held in position therein by a spring retaining ring 29 set in an internal annular groove in the uppermost part of the casing.

Surrounding the rod 27 is a guard tube 30 and adjustably clamped to the rod, at a point beyond the tube, is an arm 31 on the end of which 35 is mounted a carbon contact 31' adapted to normally rest against the side face of the contact block 20.

In operation the circuit breaker is entered into any ordinary socket, one pole of the current being 40 conducted by the shell 14 to the block 20 by the conductor 18, while the other pole is conducted by contact 22 to the helix 24, rod 27, arm 31, and carbon contact 31', which is normally engaged with the block 20, thus forming a complete circuit.

Upon imposing an overload on the circuit heat is instantly generated, causing the coiled helix to expand and move the arm 31 from the block, see Figure 4, into a remote position, as seen in 50 Figure 5, thus breaking the circuit.

The helix 24 quickly cools, re-establishing the circuit by closing the arm upon the block and conveying current therethrough.

Due to the plurality of coils in the helix it is 55

instantly responsive both in making and breaking the circuit, and obviously no labor or even attention is required.

Although the foregoing is descriptive of the preferred embodiment of the invention, it will be apparent that minor changes may be made in its construction, without departing from the scope of the claim hereto appended.

Having thus described the invention what is claimed as new and desired to secure by Letters Patent, is:—

A circuit breaker plug comprising a dielectric tubular casing having a sleeve tight fitted in one end, a dielectric disc at the outer end of said sleeve, a screw threaded conductive shell enclosing the extending portion of said sleeve and

clamping said disc thereto, a strip conductor fixed in said casing in electrical contact with said shell, a carbon block carried by said conductor to extend radially into said casing, a contact fixed centrally on said disc, a thermostatic helix in electrical engagement with said contact, said helix extending axially into said casing, a rod fixed on the extremity of said helix to pass axially therethrough, a guard tube on said rod, a contact arm supported and actuated by the outer portion of said rod to normally rest against said block and movable therefrom upon the imposition of an overload in the circuit, and a transparent cover for said casing.
